FILTER-BAG-ATTACHING DEVICE

Paul Rabatin, Kent, Ohio, assignor to The Black & Decker Electric Company, Kent, Ohio, a corporation of Ohio

Application July 15, 1938, Serial No. 219,430

2 Claims. (Cl. 285—71)

This invention relates to filtering bags for vacuum cleaners, and more particularly to the manner of attaching and detaching the bag to the suction device.

An object of my invention is to provide a quickly applied filter bag attaching and holding device, which will serve to maintain an open end of the bag in sealed relationship to the suction apparatus.

10 A further object of my invention is the provision of a simple filter bag attaching device, which may be readily inserted in the hem of the bag, and thereafter with the bag, be attached to the suction device, in such a manner as to withstand 15 a substantial longitudinal pull or stress exerted mechanically upon the bag.

Other objects of my invention will be summarized in the claims.

In the drawing, in Fig. 1 I show in cross-section an adaptation of my invention to a commercial form of vacuum cleaner; Fig. 2 is a somewhat diagrammatical illustration of the bag-attaching device, showing the form of the same when ready for insertion in the hem of the bag, 25 but before the bag is attached to the vacuum cleaner; and Fig. 3 is a view similar to Fig. 2, showing the condition of the attaching device, when the same is in bag-securing position on a vacuum cleaner of the type shown in Fig. 1.

30 In Fig. 1 of the drawing I have illustrated my invention as being adapted to the securing of a filtering bag to a vacuum cleaner of a commercial type, such as is disclosed in the Cole Patent No. 2,116,233, issued May 3rd, 1938, to my assignee.

35 In this type of vacuum cleaner, it is highly desirable to have the filter bag stretched taut, and preferably in cylindrical form. Generally such a vacuum cleaner comprises a base 10, an outer casing 11 mounted on the base, a casing closure member 12 or closure lid 12 and a motor-driven suction unit 13 carried by the lid 12 and disposed within the filtering bag 14. A suction inlet connection to the casing is generally indicated at 15 and a top guard 16 surmounts the closure lid 12. Movement of air through the device is indicated by the arrows.

The filtering bag 14 is maintained in a stretched or taut condition to prevent collapsing of the same inwardly toward the suction unit 13, and in 50 the illustration given this is accomplished by three helical spring members 18, mounted upon posts 19, which are attached to and depend from the closure lid member 12, exteriorly of the bag. The lower ends of the spring members 18 react 55 against lugs 20, formed upon or attached to a

lower metallic ring member 21, and washer members 22, carried by the posts 19. The washer members react upwardly against removable pins 23, extending through the posts. The lower ring 21 is secured to another metallic ring 24, disposed 5 interiorally of the bag.

The upper end of the bag is provided with a hem 25, and the perimeter thereof is adapted to engage, in an annularly formed, grooved flange portion 26 of the closure lid 12, and which flange 10 is disposed immediately adjacent the posts 19.

Various bag-attaching devices have been utilized to secure the open end of filter bags to vacuum cleaner casings, such as elastic bands, in the form of so-called garter springs, clamping bands, 15 cords, etc., to hold the end of the bag in suction tight relationship to some part of the cleaner casing. The usual elastic means, such as a garter spring inserted in the hem of the bag, have been found unsatisfactory, due to the fact that when 20 the cylindrical wall of the bag is maintained under sufficient tautness to efficiently function as a dust-filtering membrane, the upper end of the bag frequently becomes detached from the cleaner casing. On the other hand, when the use of positive 25 annular clamping means is resorted to, facility in rapid changing of the bag for renewal and for cleaning purposes, is impaired.

I have devised a very simple bag-attaching means which may comprise, as shown, in Figs. 2 30 and 3, a single stretch of spring wire, such as a good grade of piano wire, which can be cheaply and readily formed into the hoop shape 30a, illustrated in Fig. 2, having free end extensions 32a and 33a with a coil spring 31 formed on the extension 33a to be disposed exteriorally of the hem of the bag when the hoop portion 30a thereof is threaded through the hem of the bag.

In the particular form of the bag-securing means shown, the overall length thereof is such 40 that the ends thereof terminate in hook formations, as indicated at 32 and 33, whereby one end may be attached to one of the post members 19 and the other end 33 attached to a post member by inserting a pull on the hook end 33, to cause 45 elongation of the overall length of the wire by tensioning or stretching the coil spring section 31 thereof, as shown in Fig. 3.

It will be apparent that while the attaching means can be very simple in construction, nevertheless when attached to the bag with the hoop section 30a disposed within the bag hem and the stretches 32a, 33a and coil spring section 31 exteriorly disposed of the hem and under the tensioned condition illustrated in Fig. 3, the upper 55

end of the bag will be firmly held in contact with the closure lid flange 26, uniformly around the perimeter of the hem in opposition to the bag-stretching action of the spring members 18. The 5 hoop section of the device can be quickly threaded into the hem of the bag and the convenient attaching and detaching characteristics thereof will be apparent to those skilled in the art.

The securing action of the device is such that 10 a uniform annular snubbing and tightening force is exerted upon the bag under all operating conditions.

I claim:

1. A vacuum cleaner bag-attaching means, comprising an open end hoop formation of wire, adapted to engage within the hem of an open end of a vacuum cleaner bag and provided with extensions adapted to be disposed exteriorly of the bag hem and provided with hook-shaped ends 15

and a hoop-tensioning means connected with one of said extensions exteriorly of the bag hem, whereby the open end hoop portion of the device may be uniformly annularly tensioned against the bag end.

2. An attaching means for a vacuum cleaner bag comprising a single stretch of spring wire having an annularly formed section adapted to engage within a hem end of the filter bag, and having extensions thereon provided with hook-shaped ends adapted to be disposed exteriorly of the hem end and to engage the vacuum cleaner mechanism and one of said extensions having a contractive coil spring formation, which, when expanded and with the ends of the device attached to the vacuum cleaner, serves to exert a substantially uniform annular tension interiorly and exteriorly of the filter bag hem. 10 15

PAUL RABATIN.
